(57) **CLAIM**

The ornamental design for a water filter, as shown and described.

DESCRIPTION

FIG. 1 is a front-right perspective view of a water filter according to an embodiment of the present design;

FIG. 2 is a front-top-right perspective view thereof;

FIG. 3 is a right-side view thereof;

FIG. 4 is a left-side view thereof;

FIG. 5 is a front-side view thereof;

FIG. 6 is a back-side view thereof;

FIG. 7 is a top view thereof; and,

FIG. 8 is a bottom view thereof.

The broken lines depict portions of the water filter that form no part of the claimed design.

1 Claim, 7 Drawing Sheets
